UNITED STATES PATENT OFFICE.

THOMAS M. STACK AND WALTER R. PECK, OF NEW MILFORD, CONNECTICUT;
MARIA ANTOINETTE PECK EXECUTRIX OF SAID WALTER R. PECK, DE-
CEASED, ASSIGNOR TO SAID STACK.

COMPOSITION OF MATTER FOR REMOVING VARNISH, &c.

SPECIFICATION forming part of Letters Patent No. 747,898, dated December 22, 1903.

Application filed April 18, 1903. Serial No. 153,321. (No specimens.)

To all whom it may concern:

Be it known that we, THOMAS M. STACK and WALTER R. PECK, citizens of the United States, residing at New Milford, county of Litchfield, State of Connecticut, have invented a new and useful Composition of Matter to be Used for the Removal of Paint, Varnish, &c., from Woodwork Preparatory to Refinishing, of which the following is a specification.

The object of this invention is to provide a composition that will quickly effect the removal of either paint or varnish from surfaces which from long use or abuse have become marred to such an extent as to make refinishing necessary, it being required under such conditions that all coats of paint or varnish composing the original finish down to the bare wood be removed before the refinishing process can be commenced. It is furthermore required in a composition for this purpose that it shall be perfectly safe in use in that it shall not injure the hands of the party using it and that there be no fumes arising therefrom injurious to health, and, furthermore, that it shall not discolor or raise the grain of the wood to which it may be applied.

We are of course aware that various methods have heretofore been employed for the removal of paint and varnish, among which may be mentioned compositions including as ingredients caustics, potashes, &c., whose use is objectionable, owing to the fact that they are destructive to animal tissue and will seriously injure the hands if brought into contact therewith, and, furthermore, that the inhalation of fumes arising therefrom is seriously injurious to the health of the user. These objections are, in fact, so serious as to lead to the general use of the torch for removing paint and varnish, the danger of which is too well known to require discussion.

A further objection which may be stated to the use of all compositions of which we are aware is that they tend to materially darken woodwork and that they raise the grain of the wood, which necessitates after the complete removal of the paint or varnish and drying of the woodwork that it be thoroughly sandpapered in order to smooth the surface before refinishing, thus causing an

additional operation which is a serious item of expense.

Our novel composition consists of the following ingredients, combined in substantially the proportions stated, viz: amyl acetate, four gallons; alcohol, (wood or grain,) four gallons; benzole, four gallons; acetone, three gallons; sixty-two-degree benzin, three gallons. These ingredients are to be thoroughly mingled by agitation.

In using the above-named composition a coat of the composition is applied to the surface to be refinished, using for the purpose a brush or a cloth well saturated with the composition. The composition is allowed to remain on the surface until it assumes a gelatinous or granulated appearance, such result occurring in from five to twenty minutes and depending, of course, upon the general condition and the refractoriness of the coating to be removed. The operator may then with a wide-bladed spatula or putty-knife remove the entire coating. The surface should then be washed off to remove any of the softened coating that may not have been removed by the spatula, using a cloth saturated with either benzin or wood-alcohol, as may be preferred. This leaves the surface perfectly clean and after being allowed to dry it is ready for refinishing. Should the old coating on the surface to be refinished be a light one and not specially refractory, it may be readily removed by a brisk rubbing with a cloth well saturated with the composition. The complete removal of the old coating will be apparent by the appearance of the bare wood, after which the surface may be washed off as above described with either benzin or wood-alcohol. If an old coating is to be removed from moldings or from any surfaces containing crevices, it will be found preferable to apply the composition with a brush rather than a cloth, as the latter will not enter the crevices as well.

We wish it distinctly understood that our invention is not limited to any exact proportions of the ingredients enumerated. As stated above, either grain-alcohol or wood-alcohol may be used. In practice we have found wood-alcohol perfectly effective. Furthermore, while we preferably use the ingredients stated in their purest form their use

in the purest form is not essential to the operativeness of the composition, as the ingredients may be used in crude form instead of refined, if preferred.

5 We are of course well aware that benzin and wood-alcohol have been used as ingredients in various cleansing and removing compositions and only make claim to these ingredients when used in connection with to amyl acetate, benzole, and acetone.

Having thus described our invention, we claim—

The herein-described composition of matter consisting of amyl acetate, alcohol, benzole, acetone and benzin substantially as described and for the purpose specified. 15

In testimony whereof we affix our signatures in presence of two witnesses.

THOMAS M. STACK.
WALTER R. PECK.
